United States Patent

Des. 236,380
Patented Aug. 19, 1975

236,380

PROJECTION CABINET

Charles Topfer, Mentor, Ohio, assignor to
Rappaport Exhibits, Inc.

Filed Mar. 11, 1974, Ser. No. 449,971

Term of patent 14 years

Int. Cl. D16—02

U.S. Cl. D61—1 N

Fig. 1

Fig. 2

Fig. 3

Fig. 4

FIG. 1 is a top plan view of the projection cabinet, showing my new design;

FIG. 2 is a front elevational view;

FIG. 3 is a side elevational view; and

FIG. 4 is a rear elevational view thereof.

I claim:

The ornamental design for a projection cabinet, substantially as shown.
